ELECTRON DISCHARGE DEVICE

Andrew V. Haeff, East Orange, N. J., and Lloyd P. Smith, Ithaca, N. Y., assignors to Radio Corporation of America, a corporation of Delaware

Application September 13, 1939, Serial No. 294,612

13 Claims. (Cl. 250—161)

Our invention relates to electron discharge devices, more particularly to such devices employing a beam of electrons and suitable for use at high frequencies.

5 In devices employing electron beams it is essential that the beams be prevented from diverging. The principal causes of divergence in electron beams are (1) the mutual repulsion of the electrons themselves, (2) the defocusing of 10 the static electric fields, and (3) the defocusing produced by electric fields which vary with time. The latter is particularly objectionable in devices where electrons are required to traverse a gap across which there is a potential difference 15 which changes appreciably during the time of electron transit. This phenomena will be discussed in greater detail below. Efforts have been made to prevent or neutralize divergence by means of electrostatic fields imposed upon the 20 electrode system but in many applications this is undesirable from a practical point of view because of the necessity of introducing additional electrodes and other consequent circuit complications. While the defocusing effects may be 25 compensated for by the use of a sufficiently intense uniform magnetic field in the direction of the beam, it is sometimes difficult to produce the intense uniform magnetic field throughout the volume occupied by the beam, particularly in 30 those cases where circuit considerations do not permit the source of the magnetic field, that is the solenoid or permanent magnet, to be located in the immediate vicinity of the beam.

It is the principal object of our invention to 35 provide an improved electron discharge device utilizing an electron beam and in which undesirable convergence or divergence of the beam is substantially eliminated.

More specifically it is the object of our invention to provide such an electron discharge device 40 suitable for use at high frequencies in which the defocusing effect of the beam by the electrons in the beam or by static or varying electric fields is substantially neutralized.

45 The novel features which we believe to be characteristic of our invention are set forth with particularity in the appended claims, but the invention itself will best be understood by reference to the following description taken in connection with the accompanying drawings in which Figure 1 is a diagram showing the phenomena which are neutralized by our invention, Figures 2 and 3 are diagrams illustrating the fundamental principles involved in our invention, Figures 4 to 8 inclusive are diagrams explaining the

operation of one form of an electron discharge device to which our invention is particularly applicable, and Figures 9 to 12 are cross section partially diagrammatic views of electron discharge devices made according to our invention 5 and their associated circuits.

To illustrate the action of electric fields which result in defocusing of an electron beam when the beam passes a gap between two adjacent electrodes at different potentials, reference is 10 had to Figure 1. In Figure 1 tubular electrodes 10 and 11 are separated by a gap as indicated and an accelerating field for the electrons is provided by maintaining electrode 11 at the higher potential. The electrostatic lines of force are 15 indicated by the dotted lines 12 and the equipotential lines of force by the thin full lines 13. Electrons traveling along the parallel paths 14 as indicated in the left hand side of the figure are 20 accelerated toward the right hand side. When an electron is traveling from left to right and the potential difference is such as to accelerate the electron, the electron first encounters a radial component of electric force towards the center, that is the electrons will tend to travel at 25 right angles to the equipotential plains of force indicated in Figure 1. After crossing the center of the gap the electrons are acted upon by a radial force in an opposite direction tending to remove the electrons from the beam. Under static 30 conditions the net effect of the radial components of force is to produce convergence because the accelerated electrons will traverse the diverging part of the field in a shorter time than the converging part. That is, the electrons will be subjected to a converging field on the left side of the gap for a longer time than to a diverging field 35 of the same strength on the right side.

However, if the field increases appreciably during the electron transit time, there may be a 40 divergence of the beam because although the period of dwell within the field on the right hand side is shorter, the electrons experience a greater outward force during their transit on the right hand side as compared with the force toward the 45 center while traversing the field on the left hand side of the gap. On the other hand, if the field is decreasing during transit time, the net result will be to converge the beam more sharply than when a static field is employed. That is, although 50 the electron will dwell within the field at the right hand side of the gap for a longer period of time than at the left hand side, the forces on the right hand side are considerably weaker and thus the beam will remain focused.

If the electrons enter a retarding field, that is with the electrode 10 at a higher potential under static conditions, the electrons remain for a longer period of time on the right hand side of the gap than on the left hand side. A diverging effect is produced on the left side but the beam will converge since converging forces on the right side of the gap act for a longer period of time. If the field is being increased, that is the left hand electrode increases in potential, convergence will be even greater. On the other hand if the field is decreasing with the potential on the electrode 10 decreasing and the potential on the electrode 11 increasing in a positive direction, if the change is rapid enough divergence may result.

The various defocusing actions described above can be avoided by the use of our invention using a system of magnetic lenses. The defocusing due to the variations of the electric field with time is compensated most effectively when the magnetic field of the lens occupies the same region as the defocusing electric field.

The basic principle of our invention is illustrated in Figure 2. Surrounding the tubular electrodes 10 and 11 are tubular members 16 and 17 of ferromagnetic material, preferably iron, similar in shape to the conductors producing the electric field. That is, there is provided between these electron lens members a gap registering with the gap between the tubular electrodes. The distribution of the magnetic field is similar to that of the electric field. The magnetic field is chosen sufficiently large so that convergence of the beam is produced irrespective of the diverging effect of a rapidly changing electric field. In this figure the electric field is represented by the dotted lines and the magnetic field by the solid lines. The magnetic field of course remains constant although the electric field may change.

In such a lens the force on the electrons producing convergence depends on the square of the magnetic field intensity. As is shown in Figure 2 the magnetic field increases as the beam boundary is approached. Therefore, the outermost electrons will receive the greater focusing action so that all the electrons passing through the lens will be converged. For this reason a magnetic lens of this type has a very important advantage over the use of a uniform magnetic field. In addition the localization of the magnetic field in the regions where it is most needed makes the energy required to establish the requisite focusing field considerably less than for the uniform field. The same type of magnetic lens can be effectively used to prevent divergence from any cause such as space charge and defocusing effects of electrostatic fields.

One of the most important uses of magnetic lenses described is in connection with electron beam tubes designed for operation at high frequencies. However, the use of the lens of the form illustrated in Figure 2, where high frequency electric fields are effective, would involve large energy loss in the ferromagnetic material due to currents induced by high frequency fields in which the electrodes would be immersed during operation of the tube. In order to avoid this in accordance with our invention we coat or enclose the magnetic field producing elements with a material having a high electrical conductivity as shown in Figure 3, that is lens members 16 and 17 may be provided with a coating 10' and 11' which sheaths the members and 75 which is made of some material, for example

copper, which has a high electrical conductivity. In the application of the lens members to an electrode comprising tubular members such as 10 and 11 in Figure 2, the inner coatings may consist of the tubular members themselves. Because of the skin effect, the thickness of the conducting coating necessary to make the losses negligible can be made very small. For example, at a frequency of 500 megacycles the minimum thickness of the coating is of the order 10 of .0001 inch.

Magnetic lenses of the type described above have been successfully used for focusing an electron beam in the high frequency inductive output tubes of the type described and claimed in 15 a co-pending application, Serial No. 254,239 filed February 2, 1939, in the name of Andrew V. Haeff, one of the co-inventors of the present application, and assigned to the same assignee as the present application. In order that the 20 construction and the operation of such a tube may be understood, reference is had to Figures 4 to 8 inclusive.

In Figure 4 is schematically shown the longitudinal schematic section of a quarter wave 25 concentric line tank circuit comprising an inner tubular conductor 20 which may be cylindrical in cross section, and a hollow outer tubular conductor 21 concentric with the inner conductor 20 and electrically connected to the inner conductor 20 by the conducting plate 22. A second tubular conductor 24 which may be referred to as the aperture extension is coaxial with the conductor 20 and spaced axially from the conductor 20 to provide a gap 25. This tubular conductor 24 and the outer conductor 21 are connected by the conducting plate 23. This arrangement provides a quarter wave concentric tank circuit. If a negatively charged body 26 is projected axially through the inner conductor 20 from left to right, the conditions of the charge distribution on the circuit as the body 26 is moved along the interior of conductors 20 and 24 is indicated in Figures 4 to 6 inclusive. As shown in the figures, there is a positive 45 charge equal to the negative charge induced on the inside of the inner conductor near the body. However, initially no charge appears on the outer surface of the inner conductor 20. The induced charge moves with the charged body 50 along the inner surface of conductor 20 until the end of the inner conductor 20 is reached. During the passage of the charged body across the gap 25, the charge is partially imaged on the end of the inner conductor 20 and partially on 55 the outer conductor 24 as shown in Figure 5. The passage of the charged body beyond the gap 25 into the conductor 24 causes the induced charge all to appear on the inner surface of the conductor 24 as shown in Figure 6. The induced charge in transferring from the end of the inner conductor to the conductor 24 flows back over the outer surface of the inner conductor 20 and the inner surface of the conductor 21, thus constituting a current flow in the quarter wave tank circuit. If charged bodies are projected past the gap in proper phase and frequency relationship with respect to the resonant frequency of the tank circuit, the circuit may be made to oscillate vigorously merely by the 70 passage of the charged bodies past the gap.

Figure 7 illustrates the configuration of the electric and magnetic fields within the resonant space of the tank circuit when the latter is excited. The solid lines 27 represent the electric

field distribution and the circles 28 represent the magnetic lines of force. The dashed lines 29 represent the equipotential surfaces in the gap. Along the major part of the length of the tank circuit the direction of the electric field is substantially radial. However, at the gap 25 the electric field has an axial component. The electric field does not penetrate very far inside the open end of the inner conducting member 20 and inside the conductor 24 is essential field free, therefore no work will be done on a charge moving inside the inner conductor 20 by the electric field until the charge reaches the gap 25. If the charge traverses the gap at the instant when the electric force is in the direction from 20 to 24, the charge will be decelerated, its energy being given up to the tank circuit. A charge crossing the gap during the opposite half cycle when the field is reversed will be accelerated and absorb energy from the circuit. If, however, the number of charges traversing the gap during the first half cycle is greater than during the second, the net effect will be that energy is supplied to the tank circuit.

Thus, the tank circuit may be excited by passing groups of electrons at the proper frequency across the gap between the conductors 20 and 24. The motion of the electrons in the interior of the inner conductor 20 has no effect on the current in the tank circuit. Also high frequency electromagnetic fields, which will be generated within the resonating space of the tank circuit, penetrate but a short distance inside the conductor 20 and conductor 24 which act as a screen electrode so that the electrons will be influenced by these fields only during their passage across the gap.

In Figure 8 is shown schematically in section an electrode arrangement of a tube embodying and operating on the principle described above. Mounted within the inner conductor 20 is a conventional cathode 30 and a grid 31, which supply the pulses of electrons in the proper phase relation necessary to excite the tank circuit. A collector electrode 32 may be placed beyond the screening electrode or aperture extension 24'.

If now a high potential is applied between the cathode and the tank circuit including electrodes 20 and 24' and also between the collector 32 and cathode 30, a stream of electrons from the cathode will flow toward the collector. If a high frequency voltage is applied between the control grid and the cathode the electron stream will be periodically modulated in intensity. Pulses of electrons traversing the gap 25 will induce high frequency currents between the electrodes 20 and 24'. If the excitation frequency is adjusted to the resonant frequency of the tank circuit a high impedance will exist across the gap 25 at this frequency. The induced currents, therefore, will produce a high radio frequency voltage across the gap 25. The phase of this voltage at or near resonance will be such as to decelerate electrons traversing the gap during the half period of maximum intensity of the electron current in the stream.

The energy lost by the electrons is transformed by the tank circuit into the energy of the electromagnetic field within the resonating space between the inner and outer conductors and then may be conveyed to the useful load by means of

a coupling loop such as, for example, 33 extending through an aperture in the outer tubular conductor 21 of the tank circuit.

The high frequency electromagnetic field existing in the resonant space of the tank circuit penetrates only a short distance inside the tubular electrode 20 and inside the tubular screen electrode 24. Therefore, by positioning the control electrode 31 at a suitable distance from the gap 25 the coupling between the input electrodes 30 and 31 and the output electrodes 20 and 24' can be reduced to a negligible value. The collector electrode is also placed at an adequate distance from the gap to minimize coupling between it and the tank circuit. This results in a reduction of the losses caused by the absorption of radio frequency energy from the tank circuit by the collector.

To minimize the transit time effects the electrodes 20 and 24' can be operated at suitable high potentials with respect to the cathode. The adjustments of those potentials is not critical because the functioning of the tube does not depend critically upon the electron transit time. This is because the electrons are effective in exciting the output circuit only during the short period of time that they pass through the field extending through the gap 25. The current collecting electrode 32 can be operated at a much lower potential than the conductors 20 and 24' and in order to obtain a high efficiency it is usually operated at a potential just sufficient to collect all decelerated electrons. To improve the functioning of the device an electrostatic or magnetic focusing of the electron stream can be utilized to prevent electrons from impinging on the high potential electrodes 20 or 24. Thus these electrodes will not dissipate energy and all of the power generated in the tube will be supplied by the low voltage collector power supply.

A beam tube of the type described and embodying our present invention is shown in Figure 9. The evacuated envelope 40 contains within it the cathode 41 of the indirectly heated type, a control grid 42 and a collector electrode 43, and positioned between these electrodes the accelerating and focusing electrodes 44 and 45. A beam of electrons is directed from the cathode to the collector electrode 43. In the construction shown the concentric line tank circuit comprises the inner tubular members 46 and 47 spaced axially to provide a gap between their ends. The outer concentric tubular member 48 is electrically connected to the inner tubular members by the end discs or plates 49 and 50. The gap between the two inner coaxial cylinders is positioned between the electrodes 44 and 45.

In accordance with our invention the magnetic circuit of ferromagnetic material includes the tubular members 51, 52 and 53 positioned to provide two gaps 54 and 55, one of which registers with the accelerating electrode 44 and the other of which registers with the gap between the coaxial inner tubular members. In this way two lenses are formed. The tubular members of magnetic material forming the lens system are encased by means of highly conductive material 46' and 47' electrically connected to and forming part of the inner tubular coaxial members so that the ferromagnetic material is completely shielded from the high frequency fields. The electron beam which originates at cathode 41 is accelerated and focused by the control grid 42 and accelerating electrode 44, being finally collected at the collecting electrode 43. The lens formed by mem-

bers 51 and 52 prevents divergence of the beam caused by electrodes 42 and 44. The lens formed by the gap between tubular magnetic members 52 and 53 compensates for the divergence caused by the electric field across the gap 55. By adjusting the length of the gaps in the magnetic circuit and adjusting the current in the magnetic coil 59, the core 58 of which forms a U-shaped magnet with the legs 57 and 57', it is possible to prevent electron bombardment of electrodes 44 and 45 as well as the glass walls of the tube. The power required to do this is a small fraction of that needed when a uniform field is used.

The circuit arrangements and voltage sources are also disclosed. The leads 61 and 62 connected to the source of voltage 60 provide heating current to the heater (not shown) of cathode 41. Lead 62 connected to cathode 41 and lead 63 connected to the control electrode 42 forms with the bridging member 64 a Lecher wire system. The input circuit is connected to a driver by means of the loop 65. The tank circuit is maintained at a positive potential by means of the conductor 66 which is electrically connected to the source of supply 67. Voltage is supplied to the collector from voltage source 68, the collector being maintained at a lower potential than the tank circuit. The accelerating electrode 45 is connected electrically by conductor 45' to the positive side of voltage source 67. The load is connected to the tank circuit by means of the loop 69 extending within and coupled to the outer tubular member 48.

In Figure 10 is shown a modification of an electron discharge device made according to our invention in which the separate magnetic lenses are independently controlled by their individual magnetic circuits. Here the cathode 41 and control electrode 42 provide the modulated beam, which is collected by collector electrode 43'. The tubular members 46' and 47' with the outer tubular member 48' and the connecting side members 49' and 50' form the tank circuit. The magnetic lens tubular members 51' and 52' are separated for providing a gap registering with the gap between tubular members 46' and 47'. These electromagnetic members are coupled to the coil 59' by means of legs 72. Thus the intensity of the magnetic field across the gap can be controlled by the coil 59'. The tubular electrode 46' has adjacent and surrounding it the magnetic tubular member 74 coupled magnetically with the coil 76 by leg 75. Thus the magnetic lens within the electrode 46' and adjacent the cathode and grid can be regulated independently of the magnetic lens at the gap 73 to provide the focusing desired. These magnets could of course be permanent magnets instead of magnets 75 and 76. Within the collector electrode is mounted a rod 70 maintained at cathode potential for causing the electron beam to be spread and to prevent secondaries from leaving the collector electrode and going back to the tubular member 47'. The shield 71 prevents electrons from leaving the interior of the collector 43' through the aperture through which the rod 70 extends. This feature is covered in the co-pending application of Andrew V. Haaff, Serial No. 292,812, filed August 31, 1939, and assigned to the same assignee as the present application.

In Figure 11 is shown an arrangement whereby the output electrical circuit and magnetic lens are entirely contained within the glass envelope of the tube. The grid, cathode and collector are arranged in the manner similar to that in the

other forms of our arrangement. The tubular members 46' and 47' are electrically connected to the outer tubular member 48' to provide the quarter wave concentric line tank circuit. The tubular members of magnetic material 51' and 53' are extended around the tank circuit and have a gap registering with the gap between the tubular members 46' and 47'. These members are energized by allowing the magnetic flux produced, for example, by the cylindrical permanent magnet 59' to pass through the glass walls at d and at e, the overlapping areas d and e of internal and external magnetic material being made large enough to keep the reluctance through the glass relatively low. As in other forms a material of high electric conductivity is used on the surface of magnetic material to prevent high frequency losses.

In another form of our invention in Figure 12 we show the application of our invention to an electron discharge device utilizing a plurality of beams focused by a system of lenses formed by the grid-like structure of copper coated magnetic material as shown. Each of the beams is approximately rectangular in cross section, originating from the rectangular cathodes 80 controlled by control electrodes 81 and passing through the reduced grid-like portions 85' and 86' of the members 85 and 86 and collected by collector electrode 82 provided with rectangular shaped pockets 83 registering with the beams. The magnetic circuit for energizing the lens is common to all the lenses and coincides with the discs 90 and 91 forming with the cylindrical part 89 and the inner tubular members the electrical output circuit. The part 89 of the electrical circuit is made of non-magnetic material so that the magnetic circuit is completed through the permanent magnets 92 and 93 in contact with the discs 87 and 90, the portions of magnetic material 90 and 91 completing the magnetic circuit with the permanent magnets.

The application of our invention to tubes used in actual practice has vastly improved the operation of these tubes at high frequencies and results in a more efficient tube having stable characteristics over a wide range of frequencies. The defocusing action of the high frequency fields is substantially eliminated and bombardment of electrodes in the glass envelope by the beam is practically eliminated.

While we have indicated the preferred embodiments of our invention of which we are now aware and have also indicated specific applications for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

What we claim as new is:

1. An electron discharge device having a pair of conducting members separated by a gap, a conducting member connected to said pair of conducting members for forming an oscillating tank circuit, means for projecting a stream of electrons across said gap, magnetic means adjacent said conducting members and having a gap registering with the gap between the conducting members for providing a magnetic lens at said gap, means for modulating said stream of electrons prior to its passage across said gap and a collecting electrode for collecting electrons

- on the opposite side of said gap from said electron projecting means.
2. An electron discharge device having a pair of co-axial tubular electrodes spaced axially to provide a gap between the tubular electrodes, tubular members of magnetic material closely adjacent said axially spaced tubular electrodes and provided with a gap registering with the gap between said axially spaced tubular electrodes to 5 provide a magnetic lens at said gap, means for projecting electrons axially of said coaxial tubular electrodes across said gap, means for collecting electrons passing through said tubular electrodes, and a sheath of non-magnetic material 10 of high electrical conductivity around said tubular members of magnetic material.
3. An electron discharge device having a pair of coaxial tubular electrodes spaced axially to provide a gap between the tubular electrodes, tubular members of magnetic material closely adjacent said axially spaced tubular electrodes and provided with a gap registering with the gap between said axially spaced tubular electrodes to 15 provide a magnetic lens at said gap, means for projecting electrons axially of said coaxial tubular electrodes across said gap and means for collecting electrons passing through said tubular members, and a solenoid magnetically coupled to said tubular members of magnetic material.
- 30 4. An electron discharge device having a cathode for supplying electrons, a collector electrode spaced from said cathode for receiving said electrons, means including a pair of coaxial tubular members spaced axially to provide a gap between said tubular members, said tubular members being so positioned between the cathode and collector electrode so that electrons moving from the cathode to the collector electrode will pass axially through the tubular members across said 35 gap, and an outer concentric tubular member electrically connected to said coaxial tubular member to form a tank circuit, tubular members of magnetic material closely adjacent said axially spaced tubular members and coaxial therewith and provided with a gap registering with the gap 40 between the axially spaced tubular members to provide a magnetic lens at said gap.
5. An electron discharge device including a quarter wave concentric line output tank circuit 45 having a pair of coaxial tubular members spaced axially to form a gap and a concentric outer tubular member connected by a conducting plate at each end to one of said tubular members, a cathode and grid positioned adjacent the end of one 50 of said pair of coaxial tubular members for supplying electrons axially of said coaxial tubular members across said gap and a collecting electrode adjacent the end of the other coaxial tubular member for receiving the electrons from 55 the cathode, means including tubular members of magnetic material spaced to provide a gap registering with the gap between the coaxial tubular members for providing a magnetic lens at said gap, the electrons projected through said 60 coaxial members from said cathode to said collecting electrode being focussed into a well-defined beam by said magnetic lens.
6. An electron discharge device including 65 means for providing a beam of electrons and a collecting electrode for receiving the beam of electrons, a pair of coaxial tubular electrodes axially spaced to provide a gap and surrounding the discharge path between the cathode and anode whereby electrons from the cathode to 70 the anode traverse the gap between said pair

of coaxial tubular electrodes and an accelerating electrode surrounding the path of the beam between the cathode and the gap, tubular members of magnetic material positioned closely adjacent the tubular electrodes and provided with gaps registering with the accelerating electrode and with the gap between the coaxial tubular electrodes to provide a pair of electron lenses for said accelerating electrode and at said gap. 5

7. An electron discharge device having an envelope containing a cathode and grid for providing a source of modulated electrons, and means for forming said modulated electrons into a beam, a collector electrode for receiving said electrons, and a quarter wave concentric line tank circuit having a pair of coaxial tubular members spaced axially to provide a gap and surrounding said envelope and the discharge path between the cathode and collector electrode, and positioned so that the gap between 10 the tubular members is intermediate the cathode and collector electrode, and magnetic means adjacent said coaxial tubular members and having a gap registering with the gap between the conducting members for providing a magnetic lens 15 at said gap.

8. An electron discharge device having an envelope containing a cathode and grid for providing a modulated stream of electrons, a collector electrode for receiving said electrons, and a quarter wave concentric line tank circuit having a pair of coaxial tubular members spaced axially to provide a gap surrounding said envelope and the discharge path between the cathode and collector electrode, and positioned so that the gap 20 between the tubular members is intermediate the cathode and collector electrode, an accelerating electrode adjacent said grid and tubular members of magnetic material adjacent and coaxial with said coaxial tubular members and 25 having a gap registering with the gap between the coaxial tubular members and a gap adjacent the accelerating electrode for providing a magnetic lens 30 at said gap and for said accelerating electrode. 35

9. An electron discharge device provided with means for providing a projected beam of electrons, a collector electrode for receiving said electrons, a pair of tubular coaxial electrodes spaced axially to provide a gap and surrounding the discharge path of said beam and positioned 40 between said electron beam supplying means and the collector electrode, and tubular members of magnetic material adjacent the tubular electrodes and surrounding the discharge path and 45 having a gap registering with the gap between the tubular electrodes and a gap adjacent the beam supplying means whereby a pair of electron lenses is provided for maintaining the beam of electrons focused during operation of the 50 tube. 55

10. An electron discharge device provided with means for providing a projected beam of electrons, a collector electrode for receiving said electrons, a pair of tubular coaxial electrodes spaced axially to provide a gap and surrounding the discharge path of said beam and positioned 55 between said electron beam supplying means and the collector electrode, and tubular members of magnetic material surrounding the discharge 60 path adjacent the tubular electrodes and having a gap registering with the gap between the tubular electrodes and a gap adjacent the beam supplying means whereby a pair of electron lenses is provided for maintaining a beam of 65 electrons. 70

electrons focused during operation of the tube, and solenoid means operably associated with the magnetic tubular member for individually controlling the magnetic field produced at each 5 gap between the tubular members of magnetic material.

11. An electron discharge device including a cathode and a grid for providing a modulated stream of electrons, a collector for receiving said 10 electrons, a quarter wave concentric line tank circuit having a pair of coaxial tubular electrodes spaced axially to provide a gap and surrounding the discharge path between the cathode and collector and positioned so that the gap between 15 the tubular electrodes is intermediate the cathode and collector, an accelerating electrode adjacent said grid and tubular members of magnetic material adjacent and coaxial with said axial tubular members and having a gap registering with the gap between the coaxial tubular 20 members and a gap adjacent the accelerating electrode for providing a magnetic lens at said gap and for said accelerating electrode.

12. An electron discharge device having a plurality of beam supplying means for supplying a plurality of parallel beams and means for collecting said beams, tubular electrodes provided with a plurality of apertures registering with said beams and spaced to provide a gap through 25 which said beams are projected, magnetic means surrounding said apertures and having a gap

registering with the gap between the tubular members, extensions from said magnetic means and permanent U-shaped magnets cooperating with said extensions to provide a magnetic circuit whereby a magnetic field is produced at 5 said gaps to provide a magnetic lens for said beams of electrons.

13. An electron discharge device having an envelope containing a cathode and a grid for providing a source of modulated electrons, a collector for receiving said electrons and a quarter wave concentric line tank circuit having a pair of coaxial tubular members spaced axially to provide a gap and surrounding the discharge path between the cathode and collector electrode 10 and positioned so that the gap between the tubular electrodes is intermediate the cathode and collector electrode, magnetic means adjacent and coaxial with the coaxial tubular electrodes and having a gap registering with the gap between the tubular electrodes for providing a magnetic lens at said gap, and radial extensions connected to said magnetic means extending to the interior surface of the envelope, and a permanent electromagnet of tubular shape surrounding the exterior of said envelope and positioned to complete a magnetic circuit through 15 said extensions on said magnetic means.
